RUNWAY FORMING AND LOAD RECEIVING
MULTIPLE CAR ASSEMBLY

Dale I. Hayes, Spokane, Wash., assignor to American Zinc, Lead and Smelting Company, St. Louis, Mo., a corporation of Maine

Application May 19, 1955, Serial No. 509,463

5 Claims. (Cl. 104—137)

My invention relates to a runway forming and load receiving multiple car assembly which is adapted for use with self-loading transports such for example as that shown in my prior patent application, Ser. No. 482,009, filed January 17, 1955, for a Self-Loading Transport and Dump Gate Therefor and now Patent Number 2,743,828 dated May 1, 1956.

The self-loading transport is particularly adapted for loading and carrying away the earth or ore from the face of a cut or tunnel. It is the principal purpose of this invention to provide a car assembly which can be brought into the cut or tunnel on rails and which provides a runway upon which the self-loading transport and its tractor can travel so that the load in the transport can be deposited in the cars and the transport can be returned to the loading face in a simple and efficient manner. My invention contemplates the provision of a multiple car assembly wherein load carrying cars and ramp forming cars are so constructed as to form a runway over the assembly from the floor level of the cut or tunnel upon which the transport can be moved to load the cars, the entire car assembly, including the ramp forming cars, being movable as a train, wherein the several units are articulated together for rail travel.

It is also the purpose of my invention to provide a runway forming and load receiving multiple car assembly of the type above described, with means operable to limit the end play in the assembly while the cars are being loaded so that the end thrust transmitted by the transport in moving onto or off the car assembly is prevented from displacing the cars or causing accumulated slack to create undue impact forces lengthwise of the cars.

In particular my invention contemplates the provision of an assembly of load receiving cars and ramp forming cars wherein the car structure embodies a runway along the longitudinal sides of the load receiving and ramp forming cars. This runway is so integrated with the sides of the cars as to provide a structural beam capable of supporting the entire load of the self-loading transport and the tractor which operates it. The cars are spring supported on the usual trucks and my invention includes means cooperating with the cars to prevent the heavy load of the transport from causing excessive deflection of the springs which normally support the car boxes on the trucks. The car body construction employed is of a well known dump bottom construction so that the load of the car is dumped through the bottom. This construction, however, forms no part of my invention and has not therefore been illustrated in detail.

The nature and advantages of my invention will appear more fully from the following description and the accompanying drawings wherein a preferred form of the invention is illustrated. The drawings and description are illustrative only and are not intended to limit the invention except insofar as it is limited by the claims.

In the drawings:

Figure 1 is a perspective view of a runway forming and

2

load receiving multiple car assembly embodying my invention, a self-loading transport of the type hereinbefore referred to being shown in connection with the assembly;

Figure 2 is a side view of one end of the assembly showing the ramp portion thereof and a part of one load receiving car;

Figure 3 is an enlarged plan view of a portion of the car assembly showing how the units of the assembly are articulated together;

Figure 4 is an enlarged plan view of one of the ramp forming members of the assembly, showing its connections to the two adjacent members;

Figure 5 is a sectional view taken on the line 5—5 of Figure 4;

Figure 6 is an enlarged fragmentary sectional view taken on the line 6—6 of Figure 5;

Figure 7 is an enlarged fragmentary sectional view taken on the line 7—7 of Figure 5;

Figure 8 is a fragmentary perspective view illustrating how the lowermost ramp forming member folds up for transport;

Figure 9 is a view in side elevation of one of the load receiving cars illustrating how it is supported, when being loaded, in such a way as to protect the springs from excessive compression;

Figure 10 is a sectional view taken on the line 10—10 of Figure 9;

Figure 11 is a plan sectional view showing the connection between two adjacent cars;

Figure 12 is a fragmentary side view, looking at Figure 11 from the side;

Figure 13 is another fragmentary view looking at Figure 11 from the side, but showing the parts that interlock the cars in a changed position;

Figure 14 is an enlarged sectional view taken on the line 14—14 of Figure 11;

Figure 15 is a perspective view of the interlocking element that is used between cars and ramp forming members; and

Figure 16 is an enlarged fragmentary sectional view taken on the line 16—16 of Figure 11, illustrating how the element shown in Figure 15 is pinned to a car.

Figure 17 is an enlarged fragmentary side view of a portion of a runway with the track laying support for the transport thereon, showing a slight modification in the runway.

Referring now to the drawings and in particular to Figure 1, the runway forming and load receiving multiple car assembly is shown with a self-loading transport 1 thereon. This self-loading transport is of the type described in my prior application. It is supported at the front end by track laying wheels 2 and 3 and at the rear end by a powered vehicle 4 which has track laying wheels 5. The car assembly embodies a plurality of load receiving cars 6 combined with ramp forming cars 7 and 8. All of the aforesaid cars have wheels which are adapted to run on rails indicated at 10 and 11 in Figure 1. The ramp forming cars 8 have ground engaging ramps 9 hinged thereto at their lowermost ends. As indicated in Figure 2 the ramps 9 are adapted to fold up from the position shown in full lines in Figure 2 to the full line position shown in Figure 8 for transport. The ramps 9 have runways 12 which are provided with upstanding guides 13 along their outer edges. The runways 12 are shown in Figure 1 with a tread covering 14 which may be of a suitable composition such as rubber to provide a good grip for the track laying elements 2, 3 and 5.

The several cars 6 have runways 15 and 16 forming the flat top portions of the longitudinal side walls 6a and 6b of the cars. These runways 15 and 16 have the covering 14 thereon. They are also provided with upstanding guides 17 and 18 along their outer edges. The guides

17 and 18 cooperate to oppose transverse movement of the transport 1 or the powered vehicle 4 when travelling over the cars 6.

The ramp forming cars 7 have their longitudinal side walls 7a and 7b provided with flat top portions 19 and 20 to form runways. It will be noted that the side walls 7a and 7b decrease in depth from the end of the car 7 adjacent to a car 6 to the other end of the car 7 so as to incline the runways 19 and 20. Outer guides 21 and 22 are provided on the runways 19 and 20 for the same purpose as the guides 17 and 18.

The cars 8 also have tapered side walls 8a and 8b which decrease in depth from the ends adjacent the cars 7 to the ends of the side walls 8a and 8b. The longitudinal side walls 8a and 8b have flat top portions 23 and 24 forming runways that are inclined at the same slope as the runways 19 and 20. Outer guides 25 and 26 are provided on the runways 23 and 24.

The cars 6 are provided with body portions with bottom dump gates indicated at 27 in Figure 3 of the drawings. This body construction is well known, and since it forms no part of my invention, it will not be described in detail.

As shown best in Figures 9 and 10, the cars 6 are supported by wheeled trucks 28. Each truck 28 comprises a shaft 29 and wheels 30. Journal boxes 31 are mounted on the ends of the shafts 29 and the cars 6 are supported on the journal boxes by springs 32 that seat on the journal boxes. The cars 6 have spring seats 33 that receive the top ends of the springs 32. The longitudinal side walls 6a and 6b are so constructed as to provide strong rigid supports for the runways 15 and 16. Each of the side walls is made up of a main plate 34 that extends full length of the car 6. This plate has a V-shaped member 35 welded to it, one side of the V-shaped member forming the runway 15 or 16 and the other side extending upwardly and inwardly from the plate 34. The member 35 is also welded to the plate 34 at the outer edge of the runway 15 or 16 as indicated at 36. The guides 17 and 18 are formed by upstanding portions of the member 35 above the weld point 36, which portions are bent over as illustrated at 37 so as to form a strong upstanding guide that extends outwardly slightly from the bottom to the top. Since these guides 17 and 18 are intended to crowd the tracks 2, 3 and 5 inward and keep them from moving outwardly at either side of the car, it is essential that the guides be of such a nature as to withstand abuse to which they will be subjected. The longitudinal side walls 6a and 6b are connected at intervals throughout their length by cross members 27a of the car body 27. The car body also includes longitudinally running beams 27b which extend downwardly below the lower edges of the plate 34 and which are joined to the plates 34 and suitably reenforced by webs 27c. The dump bottom gates 27d are placed between the beams 27b. The seats 33 are bolted to L-shaped plates 38 that are welded to the plates 34 on the outside thereof.

The construction of the cars 7 and 8 are substantially the same except that the cars 7 have higher side walls 7a and 7b than the side walls of the car 8. The detailed construction of the cars 8 is illustrated best in Figures 4 to 7 inclusive. Two shafts 39 and 40 are provided for supporting the car 8. The shafts 39 and 40 have wheels 41 at the ends thereof and the shaft 39 is secured to the side walls 8a and 8b of the car 8 in the manner illustrated in Figure 6. The runway 23 is provided with depending ribs 42 and 43 which mount a bearing block 44 that receives a reduced end 45 of the shaft 39. The side wall 8a includes an outer plate 46 that extends upward from the lower edge of the rib 42. The runway 23 is bent upwardly to form the upstanding guide 25 which is also folded over as indicated at 47 for bracing. The inner edge of the runway 23 is braced by a plate 48 that extends downwardly and is welded to the rib 43. Cross

braces 49 are provided at intervals between the plates 48 and the ribs 43 throughout the length of the car 8.

The shaft 40 is mounted in the ribs 42 and 43 by a bearing block 50 in essentially the same manner as the shaft 39 is mounted in the bearing block 44. At the lowermost ends, the side walls 8a and 8b of the cars 8 are provided with lugs 51 which are apertured to receive hinge pins 52. Similar lugs 53 are provided on the ramps 9 and these lugs are apertured also to receive the pins 52. In this way the ramps 9 are hinged or pivoted to the cars 8 so they can swing up and down. The ramps 9 are linked together by a cross bar 54, shown in Figure 1.

Figures 4 and 5 also illustrate the manner in which the car assembly is latched to the rails at the end of the rail line in order to prevent the thrust of the transport and its powered vehicle from moving the car assembly along the track. The shaft 40 is used for this purpose. The rail 11 is shown as having a latch arm 54 fastened to it by a plate 55 which is bolted to the rail and which has a pivot pin 56 for the lever 54. The lever 54 has a hook portion 57 which is adapted to engage the shaft 40. A lock member 58 is pivoted on the hook member 57 and is shaped to hook around the shaft 40, as shown in Figure 5, so as to cooperate with the hook portion 57 in preventing the shaft 40 from becoming disengaged from the latch arm 54. When the latch arm 54 is to be released from the shaft 40, the lock member 58 can be raised by means of a handle 59 thereon.

The cars 7 and 8 are coupled to each other by coupling bars 60 and coupling pins 61 on the meeting ends of the cars. The cars 60 are also coupled to each other and to the cars 7 by similar coupling bars 62 and coupling pins 63.

The normal couplings provided by the coupling bars 60 and 62 and the coupling pins 61 and 63, provides a certain amount of flexibility in the connection between the cars, and a certain amount of end play as well. When the transport or its powered vehicle first enters upon the runways on a car, it tends to tip the far end of the car upward whether the car is spring supported or without springs. Such tipping can, if unlimited, lift the flanges of the car wheels most distant from the transport above the rails and cause derailment when they come down. My invention provides means to prevent such excessive tipping of any of the cars above their wheels. This means also keeps the meeting ends of the runways on adjacent cars aligned when the assembly is receiving a load. When the car assembly is being loaded, it is important that the end play between cars be eliminated. Otherwise the end thrust of the transport and its powered vehicle will be continually moving the cars and putting undue strains on the coupling members. It is also desirable to protect the springs 32 against excessive loading when the self-loading transport is moving over the cars. Normally the car load compresses the springs 32 in accordance with the amount of load. As shown in Figure 10, provision is made at 64 for limited movement of the shaft 29 up and down with respect to the car beams 27b. A simple mechanism is provided for taking care of the tipping, the lost motion between cars, and for limiting the compression of the springs 32 while the transport is moving over the cars. This mechanism is illustrated in Figures 11 to 16 inclusive. Connecting link members 65 are pivoted at both sides of one end of each car by pivot bolts 66. These link members 65 are adapted to fit between the upright bars 67 that are provided at both sides of the other end of each car excepting the cars 8. The link members 65 have apertures 68 at their free ends and the bars 67 are apertured at 69 to receive tapered locking pins 70. When the pins 70 are inserted in place, as illustrated in Figures 11, 12, 14 and 16, they connect the cars together in such a way as to take up the endwise slack.

The link members 65 have pedestals 71 thereon which are provided with inverted U-shaped rail engaging mem-

bers 72 at their lowermost ends. These rail engaging members 72 are adapted to fit down over the rails 10 and 11 when the links 65 are coupled to both cars and thus provide stops limiting the movement of the cars transversely of the rails. They also provide supports which prevent endwise tipping of a car and which will take a part of the load when the springs 32 are compressed far enough to bring the members 72 into engagement with the rails 10 and 11. The length of the pedestal 71 is calculated so as normally to leave a small space between the top of the rail and the member 72, this space however, being less than the depth of the flanges on the member 72 so that the flanges always serve to prevent excessive transverse misalignment of the runways. When the cars are on a curve, there will be some lateral displacement of the member 72 with respect to the rails, therefore the space between the flanges of the member 72 is somewhat greater than the transverse thickness of the rail, and the flanges are bevelled on their inner faces.

The links 65 are adapted to be swung up out of the way when the cars are travelling. A hook latch 73 is provided on the end of each car which carries the links 65 to hold the links 65 in a raised position.

When it is desired to lock a link 65 at the free end of one of the cars 6 in its lowered position, it is necessary to provide a separate brace member 74 which can be connected to the free end of the link 65 by a pin 75. This brace member 74 engages a stop 76 at the end of the car 6 and is held in this manner in such a position as to hold the pedestal 71 in position to engage the member 72 with the rail.

All of the runways 15, 16, 19, 20, 23 and 24 are provided with the tread covering 14. Alternatively these runways may be provided with transverse ribs 77, as illustrated in Figure 17 of the drawings. These ribs 77 are spaced apart a distance which is twice the length of the treads 78 on the track members 2, 3 and 5. These track members normally have spaces 79 between them so that the ribs 77 act as retaining cleats to keep the tracks from slipping endwise on the runways.

It is believed that the nature and advantages of the invention will be clear from the foregoing description.

Having thus described my invention, I claim:

1. A runway forming and load receiving multiple car assembly including a plurality of wheeled cars coupled together to support a load transporting vehicle thereon for travel thereover from one end of the assembly to the other and adapted to receive therein material discharged from said vehicle while it is supported thereon, each car having a fore and aft elongated body portion having a bottom wall, end walls, side walls extending upwardly from the periphery of the bottom wall, horizontally disposed fore and aft extending wheel receiving runway plates at the top of the spaced apart side walls, and an upstanding guide flange at one side edge of each of said runway plates to guide wheels thereon, the space between said runway plates being open to the bottom wall to receive discharged material while said vehicle is supported upon said runway plates, comprising means coupled between adjacent cars holding them in fixed longitudinal relation to each other while said load transporting vehicle is moving thereover, and downwardly extending means on both sides of and mounted on opposite ends of each car longitudinally aligned with the wheels of the car engaging the surface upon which the wheels travel when said vehicle is passing over the car to prevent tipping of the cars with respect to each other under an uneven load.

2. A load receiving and runway forming wheeled car adapted to support a load transporting vehicle thereon for fore and aft travel thereover and adapted to receive therein a load of material discharged from said vehicle as it travels thereover, including a fore and aft elongated body having a bottom wall, end walls and side walls extending upwardly from the periphery of the bottom wall, each of said side walls having a transversely extended

horizontal runway forming surface at its upper edge to receive the wheels of a load transporting vehicle whereby to support said vehicle thereon for movement fore and aft over the car, said horizontal runway forming surfaces being spaced apart and the space therebetween being open to the bottom wall to admit material discharged from a vehicle supported on said surfaces between the surfaces and into the body, and upstanding fore and aft extending guide members along one edge of each of said surfaces to guide a vehicle thereon comprising means secured on both sides of and at each end of the car longitudinally aligned with the wheels of the car engaging the surface upon which the wheels travel when a vehicle is passing over the car to prevent tipping of the car with respect to the adjacent car under an uneven load.

3. A runway forming and load receiving multiple car assembly including a plurality of wheeled cars coupled together and mounted on rails and to support a load transporting vehicle thereon for travel thereover from one end of the assembly to the other and adapted to receive therein material discharged from said vehicle while it is supported thereon, each car having a fore and aft elongated body portion having a bottom wall and end walls, and side walls extending upwardly from the periphery of said bottom wall, horizontally disposed fore and aft extending wheel receiving runway plates at the top of the spaced apart side walls, and an upstanding guide flange at one side edge of each of said runway plates to guide wheels thereon, the space between said runway plates being open to the bottom wall to receive discharged material while a vehicle is supported upon said runway plates, comprising releasable longitudinally rigid interlocking elements on both sides of and connecting adjacent cars preventing endwise movement of one car with respect to the other, and downwardly extending rail engaging portions on said interlocking elements preventing vertical tipping movement of the adjacent car ends.

4. In a load receiving and runway forming multiple car assembly including a plurality of wheeled cars coupled together, each adapted to support a load transporting vehicle thereon for travel from one end of the assembly to the other and adapted to receive therein material discharged from said vehicle when it is supported thereon, the improvement in means for supporting adjacent cars against movement with respect to each other and against endwise tipping comprising transversely spaced link members pivoted at one end of certain cars connectible to the adjacent ends of adjacent cars to secure them in fixed longitudinal relation to each other, and downwardly extending means mounted on each link means to engage with the surface upon which the wheels travel when said vehicle is passing over the car preventing tipping of the car under an uneven load.

5. In a load receiving and runway forming multiple car assembly including a plurality of wheeled cars coupled together, each adapted to support a load transporting vehicle thereon for travel from one end of the assembly to the other and adapted to receive therein material discharged from said vehicle when it is supported thereon, the improvement in means for supporting adjacent cars against movement with respect to each other and against endwise tipping comprising transversely spaced interlocking members mounted at one end of certain cars, manually releasable means connecting said interlocking members to the ends of adjacent cars whereby to support the cars in fixed longitudinal relation to each other, and depending pedestals on said members to engage the surface upon which the cars travel when the members are connected between adjacent cars to prevent endwise tipping of the cars.
